UNITED STATES PATENT OFFICE.

CHARLES B. PRICE, OF PITTSBURG, PENNSYLVANIA.

RAILROAD-FROG.

SPECIFICATION forming part of Letters Patent No. 323,596, dated August 4, 1885.

Application filed January 30, 1885. (No model.)

To all whom it may concern:

Be it known that I, CHARLES B. PRICE, a citizen of the United States, residing at Pittsburgh, in the county of Allegheny and State of Pennsylvania, have invented certain new and useful Improvements in Railroad-Frogs, of which the following is a specification.

My invention relates to that class of railroad-frog crossings illustrated and described in the Letters Patent of the United States granted to me January 13, 1885; and my invention consists in certain improvements, fully described hereinafter, intended to secure greater efficiency and certainty of operation in the device.

In the drawings, Figure 1 is a plan view showing main and branch tracks of a railroad, a switch, and my improved frog-crossing and operating appliances. Fig. 2 is the same showing the parts in a different position with operating appliances of a different character. Fig. 3 is a cross-section enlarged on the line 1 2, Fig. 1. Fig. 4 is a cross-section on the line 3 4, Fig. 1. Fig. 5 is an enlarged detached view of the frog-rail. Fig. 6 is a view showing the sides of the lead-rail and main rail, and frog-rail on the latter, looking in the direction of arrow *a*, Fig. 1.

In Letters Patent issued to me January 13, 1885, I described a frog movable over and from a rail of the main track and affording a bridge over the main-track rail between one of the siding-rails and the lead-rail, so that when the frog was in position to direct the cars to the siding there would be an unbroken track between the lead-rail and the siding-rail. This bridge would therefore cross the main track where the siding was open, so that it was then necessary for the flanges of the wheels to move on a path above the top of the main rail.

My present invention has for one of its objects to maintain the main track continuous and open at all times, avoid the raising of the wheel-flanges to any material extent above the tops of the main rail when passing along the main track, and at the same time dispense with ordinary stationary frogs and secure the advantages incident to the movable frog-crossing set forth in my said Letters Patent, and this I effect by constructing and arranging the movable frog-rail so that while it may be brought above the main rail in position to di-

rect the cars onto the branch track, it will never extend beyond the inner side of the main rail or close the space between the latter and the end of the lead-rail.

My improved frog is adapted to be used in connection with any suitable form of switch. In the drawings it is shown in connection with an ordinary split switch.

A A' A'' are rails of the main track. *B* is the outside rail of the siding. *B'* is the inside rail leading from the switch to the frog, commonly known as the "lead-rail;" and *B''* is the siding-rail next to the heel or rear of the crossing or frog rail. The rails *B'* and *A''* terminate on the same line transverse to the main track and at their outer ends are brought each to a point, constituting an ordinary point-switch, which, by suitable appliances, may be set to the positions shown in Figs. 1 and 2.

A guard-rail, *C*, is parallel to the rail *B*, and a guard-rail, *C'*, is parallel to the rail *A*.

The frog-rail *E* is shown as pivoted at *x* near one end of the inner branch rail, *B'*; but it may slide laterally with like effect, and is supported by chairs or blocks *q*. The frog-rail is adapted to be brought with its inner edge, *y*, in line with the inner side of the main rail, so as to cover the latter, the tread or face *r* of the covering portion being inclined downward from the center toward each end, so that when the frog-rail is in the position shown in Fig. 1 the tread of a car-wheel passing in the direction of the arrow *b* on the main track will ride easily up over and down on said face *r* without carrying the lower edge of the flange to any material distance above the upper face of the main rail, as in the frog-rail described in my aforesaid patent. (See Fig. 3.)

In the face of the frog-rail is a groove, *w*, and at the side thereof is a tread, *s*, which is at an acute angle to the tread *y*, and when the frog-rail is in the position shown in Fig. 1 it is in line with the tread of the lead-rail *B'*, and crosses the main rail so far above the face thereof that the wheels may pass from the lead-rail upon the tread *s*, and with their flanges in the groove *w* over the main rail onto the rail *B''* of the siding.

The end of the lead-rail is at sufficient distance from the side of the main rail to leave a flange-way for the passage of the flanges of the wheels of cars moving on the main track,

and the lead-rail is gradually deepened or thickened toward its end, so that its tread at its extreme end will be on a level with the tread *s* of the frog-rail when the latter is in the position shown in Fig. 1.

The end of the lead-rail is in such position that its highest portion or tread will be opposite the end of the highest part of the tread *s* of the frog-rail *E* when the latter is in the position shown in Fig. 1, and will extend to both sides of said point, so that in passing from the lead-rail the treads of the wheels will take their bearing on the tread *s* of the frog-rail before they leave the lead-rail, and vice versa, a practically continuous tread being thus secured, notwithstanding the separation of the lead and frog rails, whereby all jolting and jars in crossing over the main rail are prevented.

If the end of the lead-rail terminate abruptly, there would be danger of accident from the striking of the cars by brake-beams hanging too low, or by pilots or other parts set too low, for which reason I prolong the said end and incline it to form an inclined face, *z*, which any low hanging parts will strike, and which will lift them gradually without injury until they pass over the top of the rail.

In place of forming the end of the lead-rail itself of the shape described, a separate casting or forging, *V*, may be used in connection with ordinary *T*-rails to constitute the lead-rail, the said casting or forging constituting, in effect, a part of the lead-rail, and being spiked firmly down upon the ties in position to form a continuation of the other portion.

The advantage of a groove, *w*, in the crossing or frog rail *E* is that it confines the flanges of wheels passing over it strictly to the line between the lead-rail and branch rail, assisted in this respect by the guard-rail *C* opposite to it. If it be desired to reduce the weight of the frog-rail *E*, however, its grooved surface may extend but part of the way back from the point *v*, and at the point where the grooving terminates the rail *E* may be correspondingly narrowed in width.

The guard-rail *C* will of course tend to insure safety in guiding the opposite flanges of wheels passing along the main track, when, by error, engines or cars are compelled to pass over the end of the frog-rail *E* when the latter is in the position shown by Fig. 2.

In Fig. 1 I have shown the frog-rail and switch-rails connected to be operated by a switch-lever and crank-levers, as in my aforesaid patent. In some instances, however, a differently-constructed operating device may be used, and in Fig. 2 I have shown one whereby the movements may be imparted to the frog and switch rails from a cranked shaft, *H*, parallel with the main rail. The said shaft may be a single piece or in three sections, the outer sections with cranked ends, and the middle section coupled therewith and carrying the

switch-lever *g*, one crank being connected by a switch-rod, *c*, to the switch-rails, and the other by a rod, *d*, to a pin, *i*, projecting downward from a lug on the frog-rail.

By the use of a cranked rod I dispense with the multiplicity of parts necessary when bell-crank levers are employed, and by forming the crank-rod of united sections I avoid the torsion incidental to a continuous rod, as the central section may be made heavy enough to avoid twisting without the expense of a long rod of great thickness.

A spring, *s'*, of any suitable character serves to compensate for lost motion, and avoids the necessity of throwing the frog-rail back by a thrust action, as in the device described in my aforesaid patent.

Without limiting myself to the precise construction and arrangement of parts shown, I claim—

1. A frog arranged to be carried to and upon the main rail of a track, and when upon the latter to coincide at its inner edge with the inner edge of said rail, extending to the rail of the branch track and affording a tread over the main rail in line with the latter and a tread across the main rail in line with the branch rail, substantially as described.

2. The frog constructed to coincide when upon the main rail with the inner edge of the latter, and extending to the siding-rail and grooved to afford a channel across and over the main rail for the flange of the car-wheel, substantially as described.

3. The combination of the grooved movable frog adapted to be brought above the main rail and terminating at the inner edge of the latter, and a lead-rail with its inner side level with the face of the frog and extending to opposite sides of the tread of the latter to afford a continuous bearing for the tread of the wheel across the space between the lead-rail and frog, substantially as described.

4. A movable frog-rail adapted to be thrown upon without crossing the main rail, and having one groove in line with the lead and branch rails, substantially as described.

5. The combination, with the main rail and siding-rail, of a movable frog-rail provided with an edge-tread inclining upward from each end, and with a tread, *s*, at an angle to the edge-tread, substantially as described.

6. The combination, with the siding-rails and rail of the main track, of a frog-rail having a portion adapted to lie upon the main rail and constitute a tread, *r*, above the same, and with a tread leading at an angle to the tread *r* to the switch-rail, substantially as described.

7. The lead-rail increased in height at the inner stationary end, in combination with a movable frog-rail provided with a tread leading to the branch rail at the same height as the end of the lead-rail, substantially as described.

8. The combination of the main rail, mova-

ble frog-rail, lead-rail thickened at the inner end and provided with an inclined face, z , substantially as and for the purpose set forth.

9. The combination, with the movable rails of a switch, and a movable frog-rail at separated points, of a crank-shaft, H, connected to said rails and provided with a switch-lever arranged midway between the cranks to operate the switch and frog rails in unison, substantially as described.

10. The combination, with the movable rails

at different points, of the crank-shaft consisting of two crank-sections and intermediate section carrying the switch-lever, substantially as described.

In testimony whereof I have signed my name to this specification in the presence of two subscribing witnesses.
